UNITED STATES PATENT OFFICE.

ARTHUR B. MODINE, OF RACINE, WISCONSIN.

HEAT-EXCHANGE UNIT.

Application filed May 28, 1926. Serial No. 112,376.

My invention relates broadly to heat exchange devices and particularly to heat exchange units which may be employed as radiator cores in household heating apparatus or the like.

The invention has among its other objects the production of devices of the kind described which are compact, durable, efficient and of simple construction.

10 A particular object of the invention is to provide an improved device of the kind described wherein provision is made for contraction or expansion of the device when it is in operation.

15 Several forms of the invention are embodied in radiator cores, each of which comprises spaced headers or tanks communicating with each other through tubes formed of thin sheet metal, the tubes being preferably of elongated cross section and preferably having thin sheet metal fins secured thereto. Connecting the tanks are reinforcing members, each of which preferably has one end rigidly secured to one of the 20 tanks and has its other end secured to the other tank in such manner that the tank is free to move relative to the first tank when the tubes shorten or elongate, due to a change in temperature. In some instances, 25 each reinforcing member is rigidly secured to each tank and is so constructed that it will readily elongate or shorten simultaneously with the tubes.

Many other objects and advantages of the 30 construction herein shown and described will be obvious to those skilled in the art from the disclosure herein given.

To this end my invention consists in the novel construction, arrangement and combination of parts herein shown and described, 35 and more particularly pointed out in the claims.

In the drawings, wherein like reference characters indicate like or corresponding 40 parts:

Fig. 1 is a plan elevation of a radiator core embodying the invention;

Fig. 2 is a side elevation of the improved radiator core;

50 Fig. 3 is a fragmentary section taken on line 3—3 of Fig. 2;

Fig. 4 is a fragmentary section taken on line 4—4 of Fig. 2;

Fig. 5 is a fragmentary section taken on line 5—5 of Fig. 2;

Fig. 6 is a fragmentary plan view of a radiator core embodying another form of the invention;

Fig. 7 is a fragmentary section taken on line 7—7 of Fig. 6;

Fig. 8 is a fragmentary plan view of a radiator core embodying still another form of the invention; and

Fig. 9 is a fragmentary side elevation of the radiator core shown in Fig. 8.

Referring for the present to Figs. 1 to 5, inclusive, wherein I have shown a radiator core embodying one form of the invention, the reference characters 10 and 11 designate spaced headers or tanks which may be formed of any suitable material, but are preferably cast or molded. The tanks 10 and 11 communicate with each other through a plurality of tubes 12 which are preferably formed from relatively thin sheet metal, the tubes being of elongated cross section in this instance. It will be noted that one wall of each of the tanks 10 and 11 is provided with a plurality of apertures 14 through which the tubes 12 communicate with the interiors of the tanks. The tubes are preferably secured to each of the tanks by means comprising a relatively thin metallic plate 16 to which the tubes are soldered, the plate being soldered or otherwise secured to the tank. Soldered or otherwise secured to the tubes 12 are a plurality of relatively thin metallic fins 18, each fin 18 being provided with a plurality of apertures 19 through which the tubes 12 project. The thin walled tubes 12 and the relatively thin fins 18 facilitate the exchange of heat from a fluid within the tubes to the air. When the improved radiator core is employed in connection with household heating apparatus, or the like, the heating fluid is preferably supplied to either of the tanks 10 and 11 through a pipe 20 screw-threaded into the tank, the heating fluid being withdrawn from the radiator core through a second pipe 100 20 screw-threaded into the other tank. Obviously, steam, hot water or the equivalent, may be circulated through the radiator core to heat a column of air rising between the tubes 12.

The radiator core is preferably provided

105

- with reinforcing side members 23, each of which, in this instance, has one of its ends rigidly secured to the tank 10 by screws 24, or the equivalent, the other end of the side member 23 being secured to the tank 11 by screws 25, or the equivalent, which project through slots 26 formed in the reinforcing side member. It will be noted that the slots 26 extend longitudinally of the reinforcing members 23 and that the tank 11 may move relative to the tank 10. This construction is advantageous in that the tubes 12 shorten and elongate with greater rapidity and to a greater extent than the side members 23 as the heating fluid is brought directly into contact therewith. Also, the tubes 12 are generally formed from a different metal than the side members 23 and thus there will be an unequal expansion and contraction between the tubes and the side members even when both the tubes and side members are subjected to the same temperatures.
- Referring now to Figs. 6 and 7 wherein I have shown another form of the invention embodied in a radiator core, the reference characters 30 and 31 designate two spaced tanks which have substantially the same functions as the tanks 10 and 11 shown in Fig. 1. The tanks 30 and 31 communicate with each other through a plurality of tubes 33 which are formed from relatively thin sheet metal and are provided with fins 34 extending transversely of the tubes and preferably soldered thereto. The tanks 30 and 31 are preferably connected to each other by reinforcing side bars, one of which is shown at 35, the bar 35 being preferably rigidly secured to the tank 30 by screws 36 or the equivalent. It will be noted that throughout the greater portion of its length, the bar 35 is substantially channel shaped in cross section so that it engages the top and bottom surfaces of the tanks 30 and 31. The end of the bar 35 which is associated with the tank 31 is provided with an extension or arm 38 which is bent at 39 to extend at an angle to the remainder of the bar. The extreme end of the arm 38 is preferably secured to the tank 31 by screws or by solder as indicated at 40. It will be noted that the bar 38 is spaced from the tank 31 from the bend 39 therein to the point where it is attached to the tank. The channel shaped portion of the bar 35 is preferably held in close proximity to the tank 31 by means comprising a clip 42 embracing the bar 35 and attached to the upper and lower surfaces of the tank 31 by screws 45 or the equivalent.
- It is apparent that the tubes 33 are relatively free to expand or contract and that they may displace the tank 31 relative to the tank 30, the movement of the tank 31 being compensated for by the bent arms 38. Of course, it is understood that the arms

30 are relatively flexible to permit such movement of the tank 31 relative to the tank 30.

In Figs. 8 and 9 I have shown still another form of the invention embodied in a radiator core comprising spaced tanks 50 and 51 which have the same functions as the aforementioned tanks 10 and 11 and communicate with each other through a plurality of thin walled tubes 53 provided with fins 54. The tanks 50 and 51 are connected to each other by reinforcing side bars, one of which is shown at 55. It will be noted that the bar 55 is substantially channel shaped in cross section throughout the greater portion of its length so that it engages the top and bottom of the tanks 50 and 51. It will also be noted that the ends of the bar 55 are rigidly secured to the tanks 50 and 51 by screws 57 and 58, respectively. Intermediate its ends the bar 55 has its flanges cut away and its web is corrugated as indicated at 60. This construction permits the tanks 50 and 51 to be displaced relative to each other during the expansion and contraction of its tubes 53, as the corrugated web 60 is of such dimensions that it will readily elongate or shorten when the tubes 53 elongate or shorten respectively.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A radiator core comprising spaced tanks, tubular members extending between the tanks and communicating therewith, a reinforcing member having one of its ends rigidly secured to one of the tanks and having the other of its ends provided with a relatively flexible portion adapted to engage the other tank, and means secured to said other tank for retaining said flexible end in close proximity to said other tank.

2. A radiator core comprising spaced tanks, tubular members interposed between the tanks and communicating therewith, and spaced bars disposed on opposite sides of the tubular members and secured to the tanks to secure them to each other but permitting limited displacement therebetween.

3. A radiator core comprising spaced tanks, tubular members interposed between the tanks and communicating therewith, a plurality of spaced bars, and means for rigidly securing the ends of the bars to the tanks, said bars being provided with relatively flexible portions permitting relative displacement of the tanks when the tubular

members change in length because of temperature variations.

4. A radiator core comprising spaced tanks, tubular members interposed between the tanks and communicating therewith, a plurality of spaced bars having their ends secured to the tanks, each of said bars hav-

ing at least one of its ends bent to form a yielding portion permitting relative displacement between the tanks.

In testimony whereof, I have hereunto signed my name.

ARTHUR B. MODINE.
